Inventor:
Paul Schon,
by Henry Faber,
Attorney.

UNITED STATES PATENT OFFICE.

PAUL SCHOEN, OF GLENS FALLS, NEW YORK.

BINDING ATTACHMENT FOR SEWING-MACHINES.

SPECIFICATION forming part of Letters Patent No. 588,019, dated August 10, 1897.

Application filed August 2, 1895. Serial No. 557,992. (No model.)

To all whom it may concern:

Be it known that I, PAUL SCHOEN, a citizen of the United States, residing at Glens Falls, in the county of Warren and State of New York, have invented certain new and useful Improvements in Binding Attachments for Sewing-Machines, of which the following is a specification, reference being had therein to the accompanying drawings.

10 My invention has for its object to provide a binding attachment for sewing-machines of such construction that two pieces of work, one or both of which may have considerable fullness, may be joined together and a binding be sewed on to cover the raw edges thereof all at one operation, thus adapting a sewing-machine for use in sewing very full sleeves of ladies' dresses, shirt-waists, &c., to the waist proper, and simultaneously to apply a 15 binding which will cover the raw edges, this work all being done by means of my invention at a single operation instead of requiring several operations, as heretofore.

In carrying my invention into effect I employ a binding-holder or binder of the usual construction and arrange the same on the work-plate of the machine at an obtuse angle or at nearly a right angle to the line of the feed, and I apply to the work or throat plate 20 of the machine, closely adjacent to the needle, a binding-guide having a simple concaved guiding-face, this binding-guide being comparatively short and having its concaved face in line with the feed of the work, or nearly 25 so, said binding-guide being recessed into the throat-plate, so that the upper face of the lower limb of said guide is flush with the upper surface of the throat-plate, or approximately so. Between the binding-holder and 30 binding-guide I preferably employ what I term a "binding-guard," which assists in directing the binding from said holder to said guide. In connection with this binding-guide 35

I employ a presser-foot, which is cut away or 40 recessed on one side, so as not to interfere with the short binding-guide which is arranged mainly within the line of the presser-foot, said foot, however, having an extended upwardly-inclined toe which projects out in 45 front of the binding-guide toward the operator, so as to permit of the passage beneath the said foot and into the binding-guide of

almost any amount of fullness of goods incidental to gathers, ruffles, &c. The feed-dog, which is employed in connection with this 55 extended presser-foot and binding-guide, is a double one, having two serrated portions, one on each side of the needle of the machine, said feed-dog being partly rearward of the needle and being also extended out in front 60 toward the operator as far as or farther than the extended toe of the presser-foot, so as to assist in forcing those portions of the work having great fullness beneath the presser-foot.

65 In the accompanying drawings, Figure 1 is a perspective view of a portion of the work-plate of a sewing-machine having my invention applied thereto. Fig. 2 is a plan view of the same with the presser-foot omitted. 70 Fig. 3 is a front view, and Fig. 4 a side view, illustrative of my invention. Fig. 5 is a section on line 5 5 of Fig. 2, and Fig. 6 shows the binding-guard and gage or edge-guide in perspective.

75 A denotes a scroll-shaped binding-holder of ordinary construction and which is of U-shaped tubular form at its delivery end, said binding-holder being provided with a shank a, by means of which it may be adjustably 80 attached to the work-plate of the machine. This binding-holder is preferably arranged at an obtuse angle, or nearly at a right angle, to the line of movement of the work.

B denotes an open binding-guide arranged 85 closely adjacent to the needle of the machine, and consisting simply of a slightly-flaring U-shaped piece of metal, the lower limb of which is recessed into the throat-plate b, so that the upper surface of said lower limb is about flush 90 with the upper surface of said throat-plate. The open binding-guide B is so arranged that its U-shaped guiding-surface extends approximately in the line of the feed of the work.

95 C denotes the presser-foot, having a recess c, which receives the binding-guide B, the toe of the said presser-foot being upwardly inclined and extended forward toward the operator in front of the said binding-guide, so 100 that any desired fullness of work can be fed in beneath the said presser-foot with its edge received by the binding-guide B and the doubled binding which passes through said guide

and which is to be sewed onto the raw edges of the material simultaneously with the operation of joining two parts of a garment together.

5 D denotes the feed-dog, which is a double one, the two portions of said dog being on opposite sides of the needle, said feed-dog extending not only rearwardly of the needle, but also well forward, so that its front end toward the operator is as far forward as the upwardly-inclined extended toe of the presser-foot.

Interposed between the binding-holder A and the binding-guide B, I preferably employ 15 an open binding-guard E, which is carried by a shank e, attached to the throat-plate of the machine in such a manner that the lower edge of the said guard will be lifted slightly above the said throat-plate. I also preferably employ a gage or edge-guide f, consisting of an upturned lip or ledge forming part of a plate F, attached to the throat-plate of the machine beneath the shank e, carrying the binding-guard E.

25 In the operation of my invention the binding strip or tape is passed through the binding-holder A, and in so doing is folded into U shape in cross-section when delivered from the U-shaped tubular end of said holder, the 30 binding passing in this form over the binding-guard E, which assists in directing it properly to the binding-guide B, where the binding is now reversed in form, so that what was the convex side of the folded binding in 35 passing out of the delivery end of the binding-holder A and over the binding-guard E becomes the concave side of the folded binding as the latter is passed through the binding-guide B, so that the work passing beneath 40 the presser-foot is inclosed by the binding which moves forward to the needle with the work, the edge of the latter opposite to and rearward of the needle being held by the operator against the gage or edge-guide f as the 45 work is fed forward. Owing to the fact that the binding-guard is so placed that its lower edge is slightly above the throat-plate the lower edge of the binding can extend slightly beneath the same as it passes forward to the 50 binding-guide, and owing also to the fact that the latter is recessed slightly into the throat-plate, so that the upper surface of its lower limb is about flush with the throat-plate, the lower edge of the binding can be easily 55 guided beneath the edge of the work, so that the binding will not fail to properly inclose both edges of the latter, there being no difficulty in directing the upper edge of the binding properly with reference to the edge of the 60 work.

Thus with the use of the several parts constituting my invention, arranged and operating as described, two parts of a garment, one or both of which may be very full, owing to gathers therein, may be sewed together, and 65 simultaneously with this operation a binding to cover the raw edges of the work may be applied to the garment-sections thus joined, thereby performing at one operation the work which has heretofore required several operations. 70

Having thus described my invention, I claim and desire to secure by Letters Patent—

1. In a sewing-machine binding apparatus, 75 the combination with a throat-plate having a recess, of an open binding-guide arranged adjacent to the needle and having a U-shaped guiding-surface extending approximately in the line of the feed of the work, said guide 80 being arranged in said recess with the upper surface of its lower limb flush with the upper surface of said throat-plate, or approximately so, a presser-foot having also an upwardly-inclined toe portion extending forward of said 85 guide, a binding-holder arranged at an angle to the said binding-guide, and serving to fold the binding before it passes to the latter, a feed-dog extended forward of said binding-guide and binding-holder beneath said toe 90 portion of said presser-foot, and an open binding-guide interposed between the delivery end of the said binding-holder and the said binding-guide and slightly elevated above the work-plate. 95

2. In a sewing-machine binding apparatus, 100 the combination with a binding-guide, of a presser-foot having a notch or recess at one side in which said binding-guide is arranged and having also an upwardly-inclined toe portion extending forward of and directly in front of said guide, of a double feed-dog having two parts both of which extend forward of said binding-guide beneath the said toe portion of said presser-foot and on opposite 105 sides of the line of the needle; whereby, owing to the combined operation of the said binding-guide and extended presser-foot and double feed-dog, two parts of a garment, one or both of which may be very full, and a binding to cover the raw edges of the work, may all be simultaneously presented to the needle, 110 substantially as described.

In testimony whereof I affix my signature in presence of two witnesses.

PAUL SCHOEN.
